UNITED STATES PATENT OFFICE.

STEPHAN JOHN JOSEPH DRZEWIECKI, OF PARIS, FRANCE.

TORPEDO-LAUNCHING APPARATUS.

SPECIFICATION forming part of Letters Patent No. 708,031, dated September 2, 1902.

Application filed January 2, 1902. Serial No. 88,147. (No model.)

To all whom it may concern:

Be it known that I, STEPHAN JOHN JOSEPH DRZEWIECKI, civil engineer, a subject of the Czar of Russia, and at present residing at 5
5 Villa Damont, Rue des Bauches, Paris, in the French Republic, have invented a certain new and useful Torpedo-Launching Apparatus, of which the following is a full, clear, and exact description, and for which I have applied for Letters Patent in France October 12, 1901, (not issued;) Great Britain November 18, 1901, No. 23,269; Italy October 18, 1901; Spain October 24, 1901; Germany October 31, 1901; Hungary November 20, 1901; 15 Denmark December 4, 1901.

This invention relates to a submarine apparatus for launching torpedoes and which is suitable to be arranged upon ordinary ships as well as upon submarine and submersible boats.

This torpedo-launching apparatus consists of two principal parts, the launching apparatus, properly speaking, and the apparatus for lowering or anchoring the same below the water-level. In certain cases, when, for instance, the apparatus is intended to be arranged upon a submarine or submersible boat, the anchoring apparatus becomes useless by reason of the plunge of the boat itself.

30 In the following description I refer to the annexed drawings, upon which—

Figure 1 shows in front elevation the complete system forming the launching apparatus and the anchoring apparatus fitted to an ordinary ship. Fig. 1^b is a corresponding plan view, but considered at the moment the torpedo is launched. Fig. 2 is an end elevation of Fig. 1. Fig. 3 is a detail view in plan. Fig. 4 is another detail view, but on a larger scale. Fig. 5 is a front part elevation, on an enlarged scale, relative to the launching apparatus. Fig. 6 is a corresponding end view. Fig. 7 is a view partly in plan and with certain of the parts shown in section. Figs. 8, 45 9, 10, 11, and 12 are detail views relating to the anchoring apparatus.

I will first describe the actual launching apparatus. It consists of three sets of devices, which are the frame or cradle in which the 50 torpedo is placed, the mechanism for expelling the same, and the mechanism for unlatching and for discharging.

The cradle intended to hold the torpedo consists of a longitudinal frame 100, shaped to the exterior contour of the torpedo, regarded 55 in its diametrical plane. The two sides of this frame are connected by four transverse half collars or hoops the convexity of which is turned from the side of the boat and the opening of which is outward. Two of these 60 half-collars at a slight distance one from the other, at 1 1 and 2 2, are at the rear end of the frame toward the tail of the torpedo, and the two other half-hoops are provided, at 3 3 and 4 4, at those places which correspond with 65 the ends of the compressed-air reservoir, (supposing a torpedo of the well-known pattern is employed which is propelled by a compressed-air motor.) These last two half-hoops are furnished interiorly with small shoes, against 70 which the torpedo rests when in position. The four half-collars aforesaid are connected longitudinally by two tubes 5 5, parallel with the tubes of the frame. The whole forms a rigid and light cradle in which the torpedo may be 75 located and which may be easily lowered and raised upon the side of the boat, as will be presently explained. For submarine and submersible boats this cradle is merely fixed to the hull of the boat—upon the deck, for example. 80 The torpedo is introduced into this cradle laterally from the exterior side of the boat in such a manner that its ends corresponding with the air-reservoir bear against the small supporting-shoes of the half-hoops 3 3 and 4 4. 85 The torpedo is also maintained by two flexible bands 6 6, made of steel strips, jointed at 6^a to the under portion of the half-hoops and fitting at 7 at their upper ends into forks upon the upper part of the half-hoops by 90 means of two bolts 8 8, mounted in bayonet fashion upon a common rod 8^a, parallel to the longitudinal tube of the frame, Figs. 1, 2, 3, and 4. This rod 8^a passes through a small cylinder 9, and a portion within this is of enlarged diameter 10, forming a piston. Two pipes 11 and 12 are joined laterally to the cylinder 9. The one 11 serves to admit compressed air, which acts on the piston 10, and this displaces the rod 8^a, with the effect of 95 manipulating the aforesaid bolts 8 8. The other pipe 12 affords communication between the cylinder 9 and a tube of larger diameter 13, serving as a cylinder for a piston 14. This

cylinder 13 is jointed toward its base to a pivot fixed to the upper part of the front half-hoop. The rod 8^a is brought back to its position of rest (which is that of Fig. 4) by a 5 spring 8^b.

The mechanism for expelling the torpedo is formed as follows: The half-hoop 33 carries exteriorly two lugs, in which is journaled the axis 15 of a lever 16, termed the "expelling-lever." This device may be made of metal plate and hinges or may consist of a conical tube furnished interiorly with wood. It is provided at its end with a shoe-piece 16^a, which is shaped according to the shell of the torpedo at the place of its air-reservoir, so as to bear properly against the same. Upon the axis 15 is keyed an arm 17, jointed to the end of the piston 14. This set of parts forms the apparatus by means of which the 15 20 torpedo is expelled or swung out sidewise at the command to fire.

The unlatching and firing mechanism is composed as follows: It consists, essentially, of a frame 18, Figs. 5, 6, and 7, capable of pivoting about a shaft 18^a, which is vertical or slightly inclined to the vertical and placed at the end of the frame or cradle at 11. The frame 18 may have the shape shown on the drawing, Fig. 5, and which is similar to 25 30 that of a figure 3, so as to facilitate the passage of the tail of the torpedo above and below its horizontal axis of oscillation in case of the boat rolling, because then the torpedo as soon as it has issued from its cradle is subjected to a pitching motion by reason of the tendency of its tail toward the upper part of this arm during the rolling of the boat itself. In the frame 18 a horizontally-pivoted part 20 pivots about a horizontal shaft 19, in which 35 40 45 50 55 60 65 70 75 80 85 90 95 100 105 110 115 120 125 130 135 140 145 150 155 160 165 170 175 180 of the common bolt 8. By means of a screw-key or other suitable tool, the lever 24 is brought again toward the front and thrusting upon the head 25 of the T-piece 21 the spring 22 is compressed and the T-piece 21 enters into the tail of the torpedo. By this movement the head 25 of the T-piece causes the links 42 to move, which bring the clasps 39 into the closed position. When the studs 40 of the clasps have entered into the holes provided therefor in the tail of the torpedo, the upper end of the lever 24 is placed exactly in the boss 27 of the upper part 28 of the central aperture. In order to render the lever 24 immovable in this position, the unlatching-lever 29 is acted upon, which pushes the pointer-bolt 26 in the conical opening in the end of the said lever 24. To lock the unlatching-lever 29 in its turn in this position, the sector 45 is turned so that the end of the delivery-lever 35 is engaged by the interior of the flange of this sector. In this manner the lever 33 maintains, by means of the ring 32, the ring 31 in the position corresponding with that of the lever 29 in the closed position. This having been effected, the screw-threaded sleeve 46 is rotated, so that it bears against the end of the hollow shaft 69 of the torpedo. The apparatus is then ready for discharging or firing. In order to launch the torpedo in a predetermined direction, the sector 45 is placed, as will be presently explained, in such a position that the diameter limiting the semicircle of this sector occupies a suitable position that at the moment the torpedo has turned around the vertical pivot of the frame 18 and is in the firing direction the extremity of the lever 35 leaves the flange of the sector 45 and escapes exteriorly. The sector 45 being then placed in this position, the torpedo is pushed back exteriorly out of its cradle by means of the expelling-lever 16, as follows: At the order to fire a suitable cock arranged upon the compressed-air pipe 45 is opened, and by means of a flexible tube suitably arranged and jointed to the pipe 11 compressed air is admitted into the cylinder 9. The piston 10, which when at rest is in the position shown in Fig. 4, is then pushed forward, and by this movement of the piston out of the rod 8^a the two bolts 88 are disengaged from the buckles 77 of the flexible straps 66, which falling down allow the torpedo a free passage to pass out sidewise into the space so opened outwardly. When the piston 10 thus moved by the compressed air has reached the end of its stroke, it uncovers the pipe 12, by which the compressed air is then admitted into the cylinder 13 and drives the piston 14 toward the exterior. This piston 14, by the intermediary of the arm 17, causes the lever 16 to pivot around its axis 15, and this, by means of the shoe 16^a bearing against the torpedo, swings this latter sidewise out of the cradle. The torpedo pivots integrally with the frame 18 around the vertical axis of the same, owing to the resistance of the water,

while the boat advances, and it swings toward the rear, describing an arc x . At the moment the torpedo is in the firing position the end 70 of the delivery-lever 35, sliding upon the flange of the sector 45, which has been fixed in the position corresponding with the determined firing angle, reaches at this moment the end of the flange, it disengages itself and escapes 75 outwardly under the action of the spring 36, pushing the rings 31 and 32. These draw along the unlatching-lever 29, which disengages the pointer-bolt 26 from the end of the lowering-lever 24. This latter by the action 80 of the powerful spring 22 is brought back rearwardly, while the T-piece 21 disengages itself from the hollow shaft of the torpedo and while the head 25 of this T-piece draws by the cranks 42 the arms 41 of the clasps 39, 85 which latter each swing around through the angle y . Their ends 46 are freed from the apertures formed in the tail of the torpedo, which is then completely free and adjusted or set to the desired direction. The lever 24 90 in its movement pulls upon the wire 44, which actuates the lever for starting the motor or engine of the torpedo, (lever for admitting the compressed air,) and as soon as this latter has been lowered the wire 44 breaks under 95 the pull of the spring 22 and the torpedo starts forward under the action of propellers. Such is the working of the mechanism serving for the actual launching of the torpedo.

For submarine, submersible, or water-covered boats and in general for those which can when desired plunge beneath the surface, the mechanism above described is sufficient in itself, since the apparatus is fixed upon the deck or upon the hull itself of the boat and 100 becomes submarine when the boat plunges; but for ordinary boats it is necessary to be able to immerse the apparatus at a given moment. This is effected by the apparatus termed the "anchoring" apparatus, which I 105 will now describe, Figs. 1, 2, 8, 9, 10, 11, 12. The front half-hoop 44 and the half-collars 1122 are provided with two runners or trolleys 51 51, the upper one jointed to the axis 110 of the upper tube 5 and the lower one jointed 115 to a pin 47, to which are attached the ends of two legs 47^a, which are also joined to the two collars. These trolleys 51 travel upon four rollers 48, mounted in pairs upon parallel axes and rolling flat upon the base of the flat 120 rail or guideway 49, fixed to and passing up the side of the boat. Upon this guideway 49 (see Fig. 11) are fixed two Z-shaped rails 50 50, between which passes the contracted portion of the previously-mentioned trolleys. 125 These are furnished at such narrowed portion with two rollers 48^a, of which the axes are perpendicular to the base of the guide, so that these rollers travel upon and bear against the interior flange of one of the rails 50, according to the direction of pressure, because there is only about two millimeters difference between the diameter of the rollers and the slot or trough between the two rails 50. The trol-

ley thus bears against the rails entirely through its rollers, and since it is jointed at 47 it is able to follow the rail or guideway whatever be the profile of this, the profile depending, of course, upon the shape of the hull of the boat.

In order that the thrust should not be exerted upon the rollers when the apparatus is in its anchored position, the trolleys are provided at the part above the slot formed by the rails 50 with enlarged dovetail portions 51^a, which locate themselves between two guides 52, provided at only those places where the trolleys are when the torpedo is in the aiming position. The thrust is thus exerted entirely upon these slides or guides 52 and not upon the rollers. The upper trolley of each collar is fixed to the end of a calibrated chain passing around a graduated or marked pulley 53. The two pulleys 53 are keyed upon a common shaft 54, upon which are also keyed two drums 60 of the same original diameter as the pulleys 53. Upon these drums 60 are wound in the contrary direction to the winding of the chains 55 two flexible metallic cables 56, each of which passes over a guide-pulley 57, descends the side of the ship, bearing against small rollers or pulleys suitably arranged, passes over a return-pulley 58, arranged flat against the side of the ship, under the ends of the guideways 49, and is attached to the lower trolley of each half-collar. In the center part of the shaft 54 is keyed a worm-wheel driven by a worm 59, which can be suitably actuated by hand-power or by an electric motor. When by means of the worm 59 and worm-wheel the shaft 54 is rotated in one direction, the chains 55 slacken and the return-cables 56, winding around the drums 60, induce the cradle carrying the torpedo to descend parallel to itself to its firing position. If the shaft 54 be rotated in the opposite direction, the cables 56 become slack, and the chains 55, drawn by the two pulleys 53, cause the cradle to reascend up to the framework which is fixed upon the deck. In this position the apparatus is recharged with a new torpedo.

As has been stated above, the direction of aim depends upon the position of the sector 45. I may before submerging the apparatus fix its position to an angle determined relatively to the diametrical plane of the boat and then tack or alter position with the boat. Such is the case for submarines; but for ordinary boats it is more convenient to aim or sight the torpedo visibly, and in that case the following sighting apparatus is employed. This is made as follows: To the shaft which carries the sector 45 is joined, by means of a universal joint 61, the lower end of a vertical shaft 62, of which the upper part is held in a movable block or bearing 63, which can be lowered upon the deck when the apparatus is taken up. Upon the head of the shaft 62 is keyed a cross-piece 64, Figs. 1 and 1^{1/2}, which by means of two parallel rods 64^a forms

a parallelogram jointed to a similar cross-piece 65, keyed upon the lower part of the axis of a sighting device 66, mounted upon a movable tripod. The sighter carries an index 67 and a graduated reglet 68, in case a moving object should be aimed at. The index and reglet are furnished with sliders, which are placed one at the division corresponding with the speed of the torpedo and the other at the division corresponding with the estimated speed of the moving target, taking care to place the reglet parallel to the direction of travel of the target. The object is then sighted, the two sliders being alined upon it, and the command to fire is given. When the discharged torpedo passes in the direction of the sighted target, it starts, as has been explained above. When the cradle and the torpedo are upon the deck, the rod of the sighter is lowered along the frame. When the apparatus is lowered into the water, the rod of the sighter is raised, holding it in the air. When the torpedo has reached its firing position, the sighter-rod is placed against the side of the boat in a place for that purpose and the upper block 63 is lowered, in which the upper part of the rod 62 is caused to engage. Upon this is mounted the cross-piece 64, which can be placed in any one direction relatively to the sector 45. The tripod of the sighter is set up, and the apparatus is in position. In order that the guideways which descend the length of the side should not afford too great a resistance to the water during the travel of the boat, they are masked or shielded by means of surfaces tapered off to act as fenders and secured to the side.

Having thus described my submarine apparatus for launching torpedoes and having set forth its working, I wish to state that I may make therein various constructional modifications in whole or in part without departing from the spirit of my invention.

I claim as my invention—

1. A torpedo-launching apparatus having an unlatching mechanism consisting of a pivoted frame, pivoted claw-arms to engage the torpedo on the outside, a threaded tubular sleeve to engage the central tube of the torpedo and mechanism for releasing said claw-arms, substantially as described.

2. A torpedo-launching apparatus having an unlatching mechanism, comprising pivoted claw-arms having extensions 41, a spring, levers controlled by the spring and connected with the extensions, a lever 24 to hold the claws in latched position and means for latching and unlatching said lever 24, substantially as described.

3. In a torpedo-launching apparatus, an unlatching mechanism consisting of spring-controlled mechanism to normally hold the torpedo and a lever 24 to hold such mechanism latched, in combination with a pointer-bolt, adapted to secure the lever 24, spring mechanism adapted to withdraw the pointer-bolt

and means to hold said spring mechanism in check until the torpedo has reached a certain determined position and then release the spring mechanism, substantially as described.

5 4. An unlatching means for torpedo-launching apparatus, comprising a pivotally-mounted frame, shaped like a figure 3, and a horizontally-pivoted part therein, carrying claw-arms adapted to engage the stern of the tor-
10 pedo, substantially as described.

5 5. An unlatching means for torpedo-launching apparatus, comprising a pivotally-mounted frame, a pivoted part in the frame, claw-arms, a cross-head, links connecting the arms

15 and cross-head, a spring to operate the cross-head, a lever pivoted to the lower part of the pivoted part at one end, and passing across and holding down the cross-head, and a pointer-bolt to latch the upper part of the lever in position, as and for the purpose de-
20 scribed.

6. An unlatching means for torpedo-launching apparatus, comprising a pivotally-mounted frame, a pivoted part in the frame, claw-arms, a cross-head, links connecting the arms and cross-head, a spring to operate the cross-head, a lever pivoted to the lower part of the pivoted part at one end and passing across and holding down the cross-head, and a pointer-bolt to latch the upper part of the lever in position, a lever secured to the pointer-bolt, fulcrumed to the pivoted part and secured at its other end to a spring-pressed collar, and means for normally holding said 35 spring-pressed collar with its spring compressed and a releasing means, substantially as described.

7. An unlatching means for torpedo-launching apparatus, comprising a pivotally-mounted frame, a pivoted part in the frame, claw-arms, a cross-head, links connecting the arms and cross-head, a spring to operate the cross-head, a lever pivoted to the lower part of the pivoted part at one end and passing across and holding down the cross-head, a pointer-bolt to latch the upper part of the lever in position, a lever secured to the pointer-bolt and to a spring-pressed collar, a lever secured to the collar adapted to control its position and a de-
45 liver-lever to operate the collar-operating lever, a sector adjustable in position, normally holding said delivery-lever in check but adapted upon a sufficient movement of the pivoted frame to release said lever, as and for the pur-
50 pose set forth.

8. A torpedo-unlatching apparatus, comprising a pivotally-mounted frame, a spring-controlled lever for unlatching the torpedo from the frame, said lever having a wire con-
60 nected with the torpedo-starting mechanism of such strength that upon the release of the

latching-lever the wire will be tensioned to throw the torpedo-lever but upon the further movement of the lever the wire will be broken, substantially as described.

65

9. A torpedo-launching apparatus, comprising a cradle, a pivotally-mounted frame at one end thereof, a sleeve carrying a sector concentric with the upper pivot of the frame, means to rotate the sector independently of the frame, and an unlatching means carried by the frame and having a delivery-lever adapted to be controlled by the sector to release it when desired, substantially as de-
75 scribed.

10. A torpedo-launching apparatus, comprising a cradle, a pivotally-mounted frame at one end thereof, a sleeve carrying a sector at the upper part of said frame, a pivoted part transversely pivoted in the frame and having upwardly and downwardly depending arms, a spring-controlled cross-head mounted in the pivoted part, claw-arms and links between them and the cross-head, a slot in the cross-head, a lever passing through the slot and pivoted at its lower end to the downwardly-depending arm of the pivoted part, its upper end being latched to the upwardly-extending arm of the pivoted part, a pointer-arm to latch them, a lever for the pointer-arm, spring means to withdraw the pointer-arm, and a delivery-lever to control the said spring means itself controlled by the afore-
80 said sector, substantially as described.

11. Apparatus for sighting torpedoes, comprising a sector, a shaft to rotate it, a cross-piece 64 to the shaft, a second cross-piece, rods connecting both cross-pieces and a shaft 66 carrying an index and graduated reglet, said shaft being fast to the second cross-head, substantially as described.

12. Apparatus for launching torpedoes, comprising rails secured to the ship's side, trolleys mounted on said rails, a cradle mounted on the trolleys, chains secured to the trolleys and mechanism for winding or unwinding said chains, as and for the purpose set forth.

13. Apparatus for launching torpedoes, comprising a cradle, trolleys on which it is mounted, guideways for the trolleys, projections 52 on certain determined points of the guideway and corresponding projections 51^a on the trolley, as and for the purpose de-
110 scribed.

In testimony whereof I have signed my name to this specification in the presence of two subscribing witnesses.

STEPHAN JOHN JOSEPH DRZEWIECKI.
